UNITED STATES PATENT OFFICE

DOMINICK ROSATI, OF CHICAGO, ILLINOIS

CORK EXTRACTOR

Application filed October 29, 1928. Serial No. 315,646.

My invention relates to cork and stopper pullers or extractors and has more particular reference to a manually operated device of this type that is characterized by the provision of an entering screw which is driven into the cork or stopper by a rotary movement and is thereafter returned to its normal position by means of specially arranged operating levers or arms so that the cork or stopper is withdrawn from the bottle or container. In an article made according to my invention the insertion of the entering screw is very simple and while it is being screwed into the cork or stopper it causes the extractor arms to be raised upon opposite sides of the body due to the fact that the body rests upon the bottle neck. When it is desired to pull out the cork these arms, which have been lifted automatically to positions preferably above a horizontal plane, are forced downwardly. With the bottle or jug resting upon a table or other support very little effort is therefore required to extract a cork or stopper no matter how securely it may have been inserted into the bottle neck.

The objects of my invention reside in providing a device of the character herein disclosed that is novel and sturdy in construction, compact in the arrangement of its parts, effective in operation, and economical to manufacture so that it may be produced at a low figure and sold to users for a moderate retail price.

It is preferred to carry out my invention, and to accomplish the numerous objects thereof, in substantially the manner hereinafter fully described and as more particularly pointed out in the claims. Reference is now made to the accompanying drawings that form a part of the specification, for a better understanding of the novel features of my device.

In the drawings:—

Fig. 1 is a vertical side elevation of an extractor that is constructed in accordance with my invention, the parts being shown in their normal position which is the position in which they should be disposed when the point of the entering screw is to be inserted in the cork or stopper.

Fig. 2 is a view, similar to view 1, but showing the parts in their relative positions at the time the entering screw has been inserted or screwed into the cork or stopper the desired distance.

Fig. 3 is a fragmentary view having a portion of the holder or body broken away and in section to disclose the construction and arrangement of certain parts.

In the drawings is shown a typical or preferred manner of carrying out my invention and in these drawings the same reference characters have been employed to designate like parts wherever they appear throughout several views.

The device comprises a body or holder member that is preferably made of cast metal in the shape shown in the drawings and while the shape herein shown is desirable it will be understood the same is not necessarily required. At the upper portion of the body there is a cylindrical or tubular stub 5 having a smooth central bore 6 through which the shank of the entering screw may have free longitudinal movement so that the stub and bore provide the bearing for the shank. Below the stub 5 the body member is provided with lateral diametrically opposite lugs 7 that afford means for mounting the operating arms as will be later explained and the portion of the body member below the lugs is made wider than the stub to provide a block 8 through which the bore 6 extends so as to elongate the shank bearing. Spaced from the block a suitable distance and connected thereto by oppositely arranged parallel webs 9 is an annular socket member 10. This socket member has its interior surface of circular outline that is tapered inwardly from its outer edge as shown by the dotted line 11 in Fig. 1 so that bottles, jugs, and other containers having discharge orifices of different diameters may be accommodated.

As before stated the shank of the entering screw is positioned for movement in the elongated bore 6. This shank has transverse or lateral wings 12 at its upper end by which the structure may be rotated, and the intermediate portion of the shank is provided with a series of rack teeth 13 that are in the form

of annular ribs extending around the shaft 14 of the shank. The diameter of these ribs is such as to permit their peripheries to freely engage with the walls of the bore 6 and thereby guide the shank and the entering screw in the manner described. At its lower end the shank is reduced as at 15 and beyond the reduced portion the member is merged into a screw 16 terminating at its lower end in the impaling point 17. This lower section of the shank is similar to the ordinary cork screw.

The lugs 7 are bifurcated by providing a vertical slot passing inwardly from their edges and these slots continue through the block 8 and the stub 5 and open into the bore 6 so that guides 18 are provided that are alining and diametrically opposite each other in the body of the structure. Operating arms 19 are positioned in guides 18 and are pivotally mounted upon pins 20 that pass transversely through the bifurcated portions of the lugs 7 so as to permit arms to hinge on said pins. The ends of the arms adjacent the pins are enlarged into disk-like form and their edges are provided with teeth 21 so that these enlarged ends of the arms present the form of small segmental or mutilated gears or pinions. The diameter of these gear-like formations of the arms is such that the teeth 20 project through the vertical slots 18 and into the bore 6 to intermesh with the rack-like formation of shank in the manner shown in Fig. 2, so that by moving the arms in one direction or other the shank is moved in the opposite direction or longitudinally in its bearing.

In using this device the socket 10 is placed upon the upper end or neck of the vessel and the impaling point 17 inserted into the cork or stopper. The arms should be in the position shown in Fig. 1, that is, pendent upon the pins 20 and alongside the socket. The shank is now rotated by turning the wings 12 and the screw portion 16 of the shank is moved into the cork or stopper. This movement, of course, will draw down the shank and by means of the gear and rack construction the arms 19 become elevated to the position shown in Fig. 2. The bottle or vessel should be placed upon a rigid support, and then by grasping the arms with both hands the operator, by pushing them down, will cause the shank to move upwardly thus withdrawing the cork from the vessel because the socket is resting upon the lip of the discharge orifice. It will be found that very little exertion on the part of the operator is required to extract the cork or stopper in this manner.

60 What I claim is:—

1. A stopper puller comprising a tubular body having an elongated bore at one end and an alining socket at the opposite end that is adapted to engage a bottle neck, an integral rotatable member having means to

rotate the same on its upper end and having a stopper entering screw at its lower portion, said member being provided with integral transverse parallel ribs intermediate said means and screw, the ribbed portion of said member having free longitudinal and rotational movement in the bore of said body, and oppositely disposed toothed elements journaled on said body and entering the bore thereof to engage said ribs for withdrawing a stopper.

2. A stopper puller comprising a tubular body having an elongated bore at one end and an alining socket at the opposite end that is adapted to engage a bottle neck, an integral rotatable member having means to rotate the same on its upper end and having a stopper entering screw at its lower portion, said member being provided with integral transverse parallel ribs intermediate said means and screw, the ribbed portion of said member having free longitudinal and rotational movement in the bore of said body, oppositely disposed segmental gears extending into the body and entering the bore thereof and engaged with said ribs for moving said member longitudinally to remove a stopper, and handles projecting from said gears for rotating the latter.

Signed at Chicago, in the county of Cook and State of Illinois, this 22nd day of October, 1928.

DOMINICK ROSATI.
